DESIGN FOR A HOSE SUPPORTER

Arthur Illsche, Rye, N. Y.

Application January 30, 1940, Serial No. 89,883

Term of patent 14 years

To all whom it may concern:

Be it known that I, Arthur Illsche, a citizen of the United States, residing at Rye, in the county of Westchester and State of New York, have invented a new, original, and ornamental Design for a Hose Supporter, of which the following is a specification, reference being had to the accompanying drawing, forming part thereof.

In the drawing—

Fig. 1 is a perspective view of a hose supporter showing my new design with the members disengaged.

Fig. 2 is an edge view of the same, showing the members engaged and

Fig. 3 is a fragmentary perspective view of the outer member with the cover cap removed.

I claim:

The ornamental design for a hose supporter, as shown and described.

ARTHUR ILLSCHE.
